[57] CLAIM

The ornamental design for a telephone set base, substantially as shown and described.

DESCRIPTION

FIG. 1 is a perspective view of one side of a telephone set base showing our new design, a perspective view of the side opposite thereto being substantially a mirror image; and

FIG. 2 is an elevational view of one side thereof, the view of the opposite side being substantially a mirror image.

The undisclosed back surface of the set opposite to that shown in FIG. 1 being a plain flat surface parallel to the broad main front surface.

FIG. 1

FIG. 2
